UNITED STATES PATENT OFFICE.

ESTHER S. BROWNING, OF KEEFETON, OKLAHOMA.

TELEPHONE-EXCHANGE SYSTEM.

1,129,951.

Specification of Letters Patent.

Patented Mar. 2, 1915.

Application filed July 18, 1913. Serial No. 779,773. Renewed January 19, 1915. Serial No. 3,169.

To all whom it may concern:

Be it known that I, ESTHER S. BROWNING, a citizen of the United States, residing at Keefeton, in the county of Muskogee and 5 State of Oklahoma, have invented new and useful Improvements in Telephone-Exchange Systems, of which the following is a specification.

This invention relates to improvements in 10 exchange systems for telephone lines and the like and has particular application to an exchange system for use in railroad signal towers, offices and other analogous places whereby any one of a plurality of incoming 15 lines may be connected up with any one of a number of locals.

In carrying out the present invention, it is 20 my purpose to provide an exchange system of the class described wherein the use of corded plugs and coöperating spring jacks 25 may be eliminated and whereby it will be impossible for the operator in charge of the exchange telephone set to "listen in" when the particular incoming and local lines are 30 connected up.

It is also my purpose to provide an 35 exchange system for telephone lines and the like which will embody among other features a plurality of incoming transmission lines, and a number of local lines, means being 40 provided and operable to connect any one of the incoming lines to an exchange operator's telephone set so that such operator may ascertain the local that the party talking over the incoming line wishes to have talking communication with, means being employed and operable to connect the incoming line to the desired local line when the operator in charge of the exchange set 45 has ascertained such local.

Furthermore, I aim to provide an 50 exchange system of the class described wherein by means of a plurality of levers, one connected to the terminal of each incoming line, and a plurality of contacts forming the terminals of the locals and adapted to be engaged by the levers, any one of the incoming lines may be connected with the desired local line so that talking communication between 55 such lines will be established.

With the above and other objects in view, the invention consists in the construction, combination and arrangement of parts hereinafter set forth in and falling within the 55 scope of the claims.

In the accompanying drawings: Figure 1 is a view in front elevation of a switch board constructed in accordance with my present invention. Fig. 2 is a vertical sectional view through the board. Fig. 3 is a 60 view in side elevation of the contact member carried by each lever. Fig. 4 is a plan view of a detail of the invention. Fig. 5 is a fragmentary view of another detail of the invention, and Fig. 6 is a diagrammatic view 65 of the exchange system.

Referring now to the accompanying drawings in detail, S designates a conventional switch board structure having a breast plate 1 constructed of suitable material and 70 formed with transverse slots 2 appropriately spaced apart along the length of the plate. Suitably secured to the base of the switch board structure below the breast plate 1 are binding posts 3 spaced apart and each 75 disposed in alinement with one of the slots 2 in the breast plate. The binding posts 3 are passed through slots formed in the horizontal limbs of angle brackets 4 seated upon the base of the switch board and extending 80 upwardly therefrom and having laterally projecting ears 5, 5 formed integral with the free ends of the vertical limbs thereof and suitably spaced apart, as illustrated in Fig. 4. The ears 5, 5 of each bracket are formed 85 with alining elongated slots 6 designed to slidably receive a pin 7 and fulcrumed upon each pin 7 between the respective pair of ears and projecting through the alining slot 6 in the breast plate is a lever 8 having the 90 lower end thereof screw threaded to receive a nut 9 against which bears one end of a coiled expansion spring 10 surrounding the lower end of the lever below the fulcrum thereof, the free extremity of such spring 95 bearing against a collar 11 loosely surrounding the lower portion of the lever and abutting the ears 5, 5. Formed in the breast plate 1 upon one side of each slot 2 therein is a series of depressions 12 suitably spaced 100 apart and receiving contacts 13 having shanks 14 projecting through apertures formed in the lower walls of the depressions, the free extremities of such shanks being screw threaded to receive nuts 15 co- 105 operating with the shanks to form binding posts. Passed through each lever 8 adjacent to the upper end thereof above the breast plate is a pivot pin 16 upon which is concentrically mounted a disk 17 arranged 110

upon one side of the lever and formed upon its periphery with a radially extending lug 18 adapted to enter one or the other of the depressions adjacent to the path of movement of the lever so as to engage the contact in such depression, the inner face of the disk, at a point opposite the lug 18 having an outwardly projecting stop lug 19 formed integral therewith and adapted to engage the rear edge of the lever when the lug 18 is seated upon the contact in the respective depression, as illustrated in Fig. 2, whereby further swinging movement of the lever 8 about its fulcrum is prevented. Extending outwardly from the periphery of the disk at a point adjacent to the stop lug 19 is a manipulating finger 20 by means of which the disk may be rotated about its pivot so as to throw the lever rearwardly a slight distance and so permit the lug 18 to be withdrawn from the depression. From this construction, it will be seen that when the lug 18 is engaged in one of the depressions of the respective series, the lever 8 will be moved in an upward direction against the action of the spring 10, thereby enabling the spring to react and hold the locking lug 19 in frictional engagement with the respective edge of the lever so that accidental displacement of the lever is avoided. On the other hand, when the disk 17 is swung about its pivot point under the action of the manipulating finger 20, the lug 18 will ride out of the respective depression and so permit the spring 10 to expand and force the lever 8 downwardly whereby the periphery of the disk will frictionally engage the adjacent portion of the breast plate. Leading into the switch board S are a plurality of incoming transmission lines 21 each terminally connected to one of the binding posts 3. The uppermost contacts of the sets aline longitudinally of the breast plate as illustrated in the diagrammatic view, while the remaining contacts of the sets are similarly arranged, and connected to the top contact of each series or set is a conductor 22 extending through the coil of the magnet of a drop 23 arranged upon the switch board above the respective set or series of contacts, the free terminals of the windings of the magnets of the drops being tapped onto a common return wire or conductor 24 grounded as at 25. Normally, the levers 8 are in the up position as illustrated in Figs. 1 and 2 so that the contacts 3 and the upper contact 13 of the various sets or rows are bridged by means of the levers. From this it will be seen that when the receiver of a telephone set connected in one of the lines 21 is removed from the hook the circuit will be closed to the respective drop 23 thereby notifying the operator in charge of the switch board or exchange of the particular line calling.

Leading from the switch board S are local lines 26 each including in series a clear-out drop 27 located upon the switch board within the vision of the exchange operator, each local extending through the respective longitudinally alining contacts of the sets, as illustrated in Fig. 6. Located in each local line 26 is a single pole double throw switch 28 adapted when in one position to close the local through the contacts 75 and when in an opposite position to connect the local line to one side of the exchange operator's telephone set 29, the opposite side of such set being tapped onto the ground wire 24. A magneto generator 30 located 80 upon the switch board within convenient reach of the operator has one side grounded and the opposite side connected to the local lines 26.

From the foregoing description taken in connection with the accompanying drawings, the construction, mode of operation and manner of employing my invention will be readily apparent. When a drop 23 has been actuated as previously described, the operator in charge of the switch board breaks the circuit through the drop by rotating the disk 19 on the respective lever 8 to disengage the lug 18 from the particular contact and moves such lever downwardly within the slot 2 so as to engage the lug 18 with the next adjacent contact of the respective series or set. This manipulation of the lever and disk 17 closes the circuit from the respective transmission line 21 through a 100 portion of the line conductor 26, the switch 28 and the exchange operator's telephone set 29 thereby enabling the party on the transmission line to have talking communication with the operator in charge of the exchange. After the operator in charge of the exchange has ascertained which local is desired, the respective lever 8 is swung about its fulcrum so as to engage the lug 18 on the disk 17 with the contact 13 in the particular local, and the signal pole double throw switch subsequently manipulated to complete the continuity of the respective local line. 110

In the present instance, I have shown a telephone exchange system having a capacity of six incoming transmission lines and three local lines and in this connection I wish it to be understood that the capacity of the system may be changed or varied to suit the requirements and exigencies of each particular case.

It will be observed that each one of the levers will establish communication between the particular transmission line and any one of the locals, while by means of the single pole double throw switches 28 the electrical continuity of the locals is established and communication between the transmission lines and an exchange operator's set broken simultaneously, thereby preventing the operator 125 130

ator in charge of such set from listening in on the lines during the course of the conversation.

It will be noted that any one of the transmission lines 21 may be connected with the exchange operator's telephone set 29 and in turn connected with the desired outgoing local 26, while it is impossible, so far as my invention is concerned, to connect one of the local lines 26 with the exchange operator's telephone set 29. As previously stated, my improved telephone exchange system is particularly adapted for use in railroading and the transmission lines 21 come into the switch board from the despatcher's office, while the outgoing local lines 26 lead to the various stations along the trackway. Thus, it will be seen that any telephone set in the despatcher's office may be connected up with any one of the signal towers or stations to which the local lines lead. When conversation has ceased and the receivers of the respective telephone sets are hung up, the particular clearing out drop 27 is actuated to notify the operator that the connection between the lines may be broken.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

1. A telephone switch board comprising a breast plate having transverse slots formed therein, contacts carried by the said plate

and spaced apart adjacent to each slot and 40 forming the terminals of certain circuits, levers fulcrumed upon said switch board and movable through the slots in said breast plate and disks pivoted upon the upper ends of said levers and formed with lugs to engage said contacts.

2. A telephone switch board comprising a breast plate formed with transverse slots therein, contacts carried by said plate and spaced apart adjacent to each slot and forming 50 the terminals of certain circuits, levers fulcrumed upon said switch board and connected with the terminals of other circuits and movable through the slots in said breast plate, disks pivoted upon the upper ends of 55 said levers and formed with lugs adapted to engage said contacts and means for holding said levers against accidental movement.

3. A telephone switch board comprising a breast plate having transverse slots formed 60 therein, contacts carried by said plate and spaced apart adjacent to each slot and forming the terminals of certain circuits, levers fulcrumed upon said switch board and connected with the terminals of other circuits 65 and movable through the slots in said breast plate, disks pivoted upon the upper ends of said levers and formed with lugs adapted to engage said contacts, and a lug projecting outwardly from each disk and adapted to 70 engage the adjacent lever end to hold the lever against accidental movement.

In testimony whereof I affix my signature in presence of two witnesses.

ESTHER S. BROWNING.
